US00D686215S

(12) **United States Design Patent**
Andre et al.

(10) **Patent No.:** **US D686,215 S**
(45) **Date of Patent:** **** Jul. 16, 2013**

(54) **ELECTRONIC DEVICE**

(75) Inventors: **Bartley K. Andre**, Menlo Park, CA (US); **John M. Brock**, San Francisco, CA (US); **Matthew Phillip Casebolt**, Fremont, CA (US); **Brett William Degner**, Menlo Park, CA (US); **Ron Alan Hopkinson**, Campbell, CA (US); **Eugene Kim**, San Francisco, CA (US); **Chris Ligtenberg**, San Carlos, CA (US); **John Raff**, Melon Park, CA (US); **David Yeh**, Redwood City, CA (US)

(73) Assignee: **Apple Inc.**, Cupertino, CA (US)

(**) Term: **14 Years**

(21) Appl. No.: **29/406,062**

(22) Filed: **Nov. 9, 2011**

Related U.S. Application Data

(62) Division of application No. 29/388,769, filed on Apr. 1, 2011, now Pat. No. Des. 652,041, which is a division of application No. 29/379,432, filed on Nov. 19, 2010, now Pat. No. Des. 637,193.

(57) **CLAIM**

The ornamental design for an electronic device, as shown and described.

DESCRIPTION

FIG. 1 is a top, front, left perspective view of an electronic device showing our new design;

FIG. 2 is a top view thereof;

FIG. 3 is a bottom view thereof;

FIG. 4 is right side view thereof;

FIG. 5 is a left side view thereof;

FIG. 6 is a rear view thereof; and,

FIG. 7 is a front view thereof.

The broken lines are for the purpose of illustrating portions of the electronic device and form no part of the claimed design.
